HELICOPTER TOY

Norman Spiegel, New York, N.Y., assignor to
Nasta Industries, Inc.

Filed Apr. 5, 1971, Ser. No. 131,569

Term of patent 14 years

Int. Cl. D21—01

U.S. Cl. D34—15

FIG. 2

FIG. 3

FIG. 1 is a perspective view generally from the rear and above of a toy helicopter embodying my new design;

FIG. 2 is a side elevational view thereof; and

FIG. 3 is a front elevational view thereof.

The design is symmetric from side to side along the longitudinal axis and the side not shown is a mirror image of the side shown.

I claim:

The ornamental design for a helicopter toy, as shown and described.
